DESIGN FOR A COMBINED BOX AND DISPLAY STAND

Guy T. Gibson, New York, N. Y.

Application September 23, 1937, Serial No. 71,737

Term of patent 14 years

To all whom it may concern:

Be it known that I, Guy T. Gibson, a citizen of the United States of America, residing in New York city, in the Borough of Manhattan, county and State of New York, have invented a new, original, and ornamental Design for a Combined Box and Display Stand, of which the following is a specification, reference being had to the accompanying drawing, forming part thereof, wherein,

Figure 1 is a side elevational view of the combined box and display stand, showing my design,

the box being lifted in order to illustrate the display stand; and,

Figure 2 is a perspective view of the combined box and display stand in its closed position.

Figure 3 is a front view of the display stand, shown in Figure 1.

I claim:

The ornamental design for a combined box and display stand, substantially as shown, and described.

GUY T. GIBSON.
